UNITED STATES PATENT OFFICE.

WILLIAM RODERICK BARCLAY, OF LEICESTER, ENGLAND, ASSIGNOR TO UNITED SHOE MACHINERY CORPORATION, OF PATERSON, NEW JERSEY, A CORPORATION OF NEW JERSEY.

SUPPORT.

Application filed June 20, 1924, Serial No. 721,192, and in Great Britain November 17, 1923.

This invention is concerned with supporting or positioning the work or a tool in operations on shoes or parts thereof, and particularly relates to the supporting of shoes 5 when on their lasts by a projection, known as a last-pin or spindle, which enters an opening in the last. Shoes are commonly supported in this manner for many operations where pressure is to be applied. 10 Among these operations may be given as examples, heel-attaching and sole-laying or leveling. Sometimes the last-engaging spindle is utilized to guide a driver for inserting a nail or other fastening to hold a heel temporarily upon a shoe, a hole being bored through the cone of the last for this purpose. This is as illustrated in British Patent No. 177,015, Haldinstein, March 23, 1922. 15 An object of the invention is to provide 20 means for distributing the pressure upon the work-support, as when a shoe and last are held upon a last-pin. Here, the effect is divided between the crown of the last and the surface engaged by the end of the pin, thus 25 avoiding the application of excessive pressure to either surface. When heels are attached, with the apparatus heretofore used, by nails driven through a hole in the last, if 30 the thickness of the last from crown to heel-seat is less than the length of the spindle which enters the last-pin-hole, the entire 35 pressure employed during the operation comes upon the end of the spindle, and this, being small in area, may be forced into the insole, leaving an undesirable depression 40 therein. Such effects I minimize by furnishing supporting members, independently movable longitudinally of the support or in the same direction under the influence of the 45 work, at least one of the members being secured against movement by retaining means controlled in such movement. More specifically, I utilize a jack having movable members to engage, respectively, a hole in the last and the last-crown, with locking means to 50 prevent such movement following the application of pressure upon one of the members. In the nailing of heels, the member entering the last-pin hole may have a passage or 55 passages to guide the fastenings and the drivers therefor.

One form of work-support or jack embodying my invention is illustrated in the accompanying drawing, in which

Fig. 1 shows the improved support in 55 work-receiving position, parts being broken away;

Fig. 2 is a central vertical section through the support, with the elements in the nail-driving relation; 60

Fig. 3 is a horizontal section on the line 3—3 of Fig. 2;

Fig. 4 is a broken detail, in side elevation, illustrating the manner of securing the drivers; and 65

Fig. 5, a perspective view of a portion of a shoe with its attached heel.

This organization may be employed, for example, in such machines as those disclosed in United States Patents No. 1,195,134, 70 Gouldbourn, Aug. 15, 1916, and No. 1,269-654, Standish, June 18, 1918. At 10 appears the top of a jack-base having reciprocating within it a driver-actuating member 12. Mounted in the upper extremity of the base 75 is the lower section 14 of the body-portion of the jack. This is preferably cylindrical, and has an axial bore to receive a plunger 16, which is aligned with the actuating member 12. To retain the plunger against accidental displacement, a slot extends vertically along one side, and is engaged by a screw 18 threaded through the jack-section 14. Normally resting on the top of the section 14 is an upper section 20 of the body-portion pivoted to the lower at 22. This allows the upper section to be swung from its operating position, shown in Fig. 2, to its work-applying and removing position appearing in Fig. 1, the movement in the latter direction being 80 limited by stop-surfaces 24 associated with the pivotal mounting. 85

Surrounding the outer cylindrical surface of the section 20 is a casing or cover-portion 25, in the top of which is an axial opening. Through this opening extends a spindle, adapted to enter the pin-hole of a last and furnished by a cylindrical projection 26 from an annular enlargement 27 fitting in the space between the casing and the reduced 100 upper extremity 28 of the section 20. Through the spindle are a plurality of longitudinal passages, of which two are illustrated, these being parallel to the axis and receiving operating tools, as drivers 105. The drivers are fixed by some such fastening device as a pin 32 entering adjacent depressions in the lower ends of the drivers, with-

in sockets formed in the end of a plunger or carrier member 34 movable in an axial bore in the section 20 and normally aligned with the plunger 16. A screw 36 extends through the section 20 with its end lying in a slot along the plunger 34. This maintains the drivers in a correct relation to the passages in the spindle. Surrounding adjacent portions of the section 20 and the casing 25, 10 with its ends abutting against the enlarged lower extremity of the latter and a shoulder upon the former, is a spring 38, which normally elevates the casing, the extent to which said casing may move in this direction being limited by a screw 40 threaded through the casing and movable into contact with the bottom of the spindle-enlargement 27. Interposed between a shoulder upon the plunger 34 and the interior of the enlargement 27 of 15 the spindle is a spring 42, which acts both to normally depress the drivers, so that their ends lie within the spindle-passages, and to raise the spindle to an extent determined by the contact of an opening through the wall 20 of its enlargement 27 with the under side of the head of a screw 44 carried at the top of the jack-section 20. Lying circumferentially about the spindle-portion 27 is a series of 25 openings to receive balls 46. The opposite sides of these balls lie in proximity to the inner wall of the casing 25 and to an inclined surface 48 surrounding the reduced portion 28 of the upper jack-section. The elements of the device are so proportioned 30 that when they are in their inactive or elevated positions, the space between the top of the casing 25 and the contact-end of the spindle 26 will be less than the height of any last, between the heel-seat-portion and 35 crown, which is to be applied to the jack. Consequently, when a shoe to which a heel is to be nailed, with its last, is placed over the spindle, the crown, upon being brought into contact with the top of the casing, forces 40 this down. This continues until the insole-surface meets the upper extremity of the spindle, depressing this. As soon as the enlargement 27 of the spindle begins its downward movement, the balls 46, by their contact with the inclined surface 48, are forced 45 into locking engagement with such surface and with the inner surface of the casing. As a result of this, both the casing and spindle are secured against further movement. 50 Thereafter, any pressure applied through the shoe and last will be resisted both by the spindle and casing, and this may be made comparatively great, to effectively hold a heel for its attachment, without causing the 55 spindle end to materially indent the insole. In using the device, the upper section of the jack is swung out upon its pivotal connection 22 from beneath the usual heel pressure member or abutment, and, the drivers 60 being held lowered by the spring 42, nails N

are supplied heads down to the passages in the spindle 26, these nails resting upon the upper extremities of the drivers 30. A last L, carrying a shoe S to be heeled, is placed over the spindle, which enters the vertical opening l in the rear portion of the last. The operator then swings back the upper jack-section to its normal position, placing a heel H in position upon the heel-seat of the shoe. Upon starting the machine, clamping pressure is applied by the heel-abutment. Under this pressure, contact of the crown of the last with the casing 25 depresses said casing until the insole, striking the end of the spindle 26, forces this down, bringing the balls 46 into locking engagement with the jack-surface 48 and the interior of the casing 25. The pressure is now uniformly distributed between the casing and the spindle-end. Then, the actuating member 12 rises, urging the plungers 16 and 34 upwardly, compressing the spring 42. The drivers, under the influence of the plunger 34, force the nails which they support through the insole of the shoe into the heel H. Since there is sometimes a tendency for the heads of the nails to break through the insole, there may be interposed between said insole and the spindle a washer W, of some such material as fiber. This washer is preferably imperforate, the 90 nails being driven through it, their heads causing it to be forced firmly against the insole. By this arrangement, the liability of the nails to pull into or through the insole is reduced by the provision of a comparatively 95 large contact-surface. Upon the descent of the actuating member 12, the elements of the jack are restored to their normal relation by the springs, upon the pressure being relieved by the rising of the heel-abutment, 100 and the upper section 25 may be again turned out about its pivot, to facilitate the 105 removal of the work.

Having described my invention, what I claim as new and desire to secure by Letters Patent of the United States is:

1. A work-support comprising supporting members movable independently longitudinally of the work-support under the influence of the work, and retaining means controlled in such movement for securing a member against movement.
2. A work-support comprising two supporting members movable independently in the same direction under the influence of the work, and retaining means controlled in such movement for securing both members against movement.
3. A work-support comprising supporting members movable independently under the influence of the work, and locking members movable by one of the supporting members and forced thereby into engagement with the associated supporting member.
4. A work-support comprising a movable

member arranged to engage the crown of a last, a movable member arranged to enter an opening in the last and to engage the work, and means controlled by the movement of one member for locking the associated member against movement.

5. A work-support comprising a body portion, a casing movable upon the body-portion, a movable spindle projecting through the casing, and locking members movable with the spindle and engaging the body-portion and casing.

6. A work-support comprising a body-portion, a casing movable upon the body-portion, a movable spindle projecting through the casing, means arranged to force the casing and spindle outwardly upon the body-portion, and locking members movable with the spindle and engaging the body-portion and casing.

7. A work-support comprising a body-portion, a casing movable upon the body-portion, a movable spindle projecting through the casing and provided with a passage, a tool movable in the passage, and locking members movable with the spindle and engaging the body-portion and casing.

8. A jack comprising a body-portion provided with an inclined surface, a casing movable about the body-portion and having a surface arranged to engage the crown of a last, there being an opening in the last-engaging surface, a spindle projecting through the opening, and locking members movable by the spindle and arranged to be forced by the inclined surface against the casing.

9. A jack comprising a body-portion provided with an inclined surface, a casing mov-

able about the body-portion and having a surface arranged to engage the crown of a last, there being an opening in the last-engaging surface, a spindle projecting through the opening, a spring interposed between the body-portion and the casing, a spring acting upon the spindle, and locking members movable by the spindle and arranged to be forced by the inclined surface against the casing.

10. A work-support comprising a body-portion provided with an inclined surface, a casing movable about the body-portion and having a surface arranged to engage the crown of a last, there being an opening in the last-engaging surface, a spindle projecting through the opening and having an enlargement extending between the body-portion and casing, there being openings through said enlargement, and balls situated in the openings and contacting with the inclined surface of the body-portion and with the inner wall of the casing.

11. A jack comprising a body-portion provided with an inclined surface, a casing movable about the body-portion and having a surface arranged to engage the crown of a last, there being an opening in the last-engaging surface, a tubular spindle projecting through the opening, a plunger movable in the body-portion, a driver secured to the plunger and extending into the casing, and locking members movable by the spindle and arranged to be forced by the inclined surface against the casing.

In testimony whereof I have signed my name to this specification.

WILLIAM RODERICK BARCLAY.
